UNITED STATES PATENT OFFICE

THOMAS LAURENCE HIBBARD, OF PUTEAUX, FRANCE

DESIGN FOR AN AUTOMOBILE ENGINE BONNET

Application filed August 23, 1928, Serial No. 27,940, and in France April 27, 1928. Term of patent 7 years.

To all whom it may concern:

Be it known that THOMAS LAURENCE HIBBARD, citizen of the United States of America, residing at Puteaux, Seine, France, has invented a new, original, and ornamental Design for an Automobile Engine Bonnet, of which the following is a specification, reference being had therein to the accompanying drawing, in which—

Figs. 1 and 2, are perspective views of the design from different points of view.

Fig. 3 is a front end view.

I claim:

The ornamental design of an automobile engine bonnet as shown.

THOMAS LAURENCE HIBBARD.
